UNITED STATES PATENT OFFICE.

J. L. HASTINGS, OF TOWANDA, PENNSYLVANIA.

IMPROVEMENT IN GOVERNORS FOR STEAM-ENGINES.

Specification forming part of Letters Patent No. 42,478, dated April 26, 1864.

To all whom it may concern:

Be it known that I, J. L. HASTINGS, of Towanda, in the county of Bradford and State of Pennsylvania, have invented certain new and useful Improvements in a Disconnecting Mechanism Applied between a Governor and the Valve which it Operates; and I do hereby declare the following to be a full, clear, and exact description of the construction and operation of the same, reference being had to the accompanying drawings, making a part of this specification, in which—

Figure 1 represents a perspective view of a steam governor and valves, with the connecting and disconnecting mechanism in place. Fig. 2 represents a transverse section through the valve-chest and valve, and Fig. 3 represents a longitudinal section through the same.

In a governor worked by a belt or band there are at least two casualties incident to such connection which cannot be provided against or avoided—viz., the breaking or parting of the belt or band, and, secondly, its liability to slip off from the pulleys; but with these liabilities to disarrangement or to damage thereby belts are much preferred to rigid gearing, such as shafts and cog-gearing, and are almost universally used.

The effect of the breaking or parting of a belt, or of its slipping off from the pulleys, is that it stops the rotation of the governor-balls, and this destroys the centrifugal force with which they are thrown out or raised, and they instantly drop, and as instantly and suddenly open wide the steam-ports, which causes a sudden and injurious accelerated motion of the engine, and sometimes serious damage.

My invention consists in interposing a mechanism between the belt that drives the governor and the valve arm or rod, which mechanism, the moment the belt parts or slips off from its pulleys, disengages the valve rod or stem from the governor, so that the dropping of the governor balls has no effect upon the valve, but allows it to remain in the position in which it was acting while connected to the governor, or may be closed entirely.

To enable others skilled in the art to make and use my invention, I will proceed to describe the same by reference to the drawings.

A is the shaft to which the arms B and balls C are hinged, as at *a a*. The arms B have pivoted to them, at *b*, the links D, the other

ends of said links being pivoted to the slide or collar E at *c*, so that the raising or lowering of the balls and their arms shall correspondingly raise or lower the slide or collar E. The shaft and governor are set in motion by means of bevel-gears or pinions, one on its lower end, the other on the end of the shaft F, over a pulley, G, on which passes a belt, H, by which said shaft is set in motion. The belt H also passes over a pulley, I, or drum, which receives its motion from the engine in any of the usual ways, and the governor is thus actuated through said belt H.

In the slide or collar E there is a groove, *e*, in which the point of the arm of a bell-crank lever, J, works, said lever being pivoted at *d* to a projection, K, on the column L, that supports the governor. To a wrist, *f*, on the lever J the connecting-rod M is connected by one of its ends by an open slot or bearing. The other end of the rod M is connected to a crank-arm, N, on the end of the valve-rod O. So far as described, the contrivance is like many others for a similar purpose, and is similarly operated. On a pillar, P, is arranged a rock-shaft, Q, one end of which has an arm, *g*, for fitting under or partially around the connecting-rod M, but not so as to interfere with said rod when the governor is working properly. To the other end, *h*, of said rock-shaft there is attached an arm, R, the extreme end *i* of which carries a pulley or wheel, S, that rests upon the endless belt H, said belt holding up the wheel or pulley in the position shown in the drawings. Should the belt H part, break, or slip off either of its pulleys G I, the wheel S would drop, the shaft Q turn, and the arm *g* raise up the connecting-rod M and disengage it from the wrist *f*, and consequently disconnect it from the governor. The sudden dropping of the governor-balls could then in no wise injuriously affect the action of the valve in the steam-chest, and no sudden starting or jarring of the engine could take place. The chain T prevents the arm *g* from turning so far as to drop the connecting-rod M, which might injure it, or which might affect the valve, but allows it to turn far enough to disengage said rod from the governor or crank J, and then is caught and held there, and far enough for the chain to close the valve.

The steam-chest U is cylindrical, and has an interior cylinder, V, within it, between which

cylinders are inlet-passages *j* and exit-passages *k*, they being separated by a partition, *l*. The valve *W* works in the inner cylinder, and opens and closes the ports *m m*, as controlled by the governor. The steam enters the chest *U* through the steam-pipe *X*, thence through the passages *n* at the ends of the passage *j* into the space in which the valve *W* works, thence in such regulated quantities as the governor through the valve may admit of, through the ports *m* and passage *k* and pipe *Y* to the engine.

It is, of course, understood that the rising and falling of the slide or collar *E*, through the influence of the governor-balls, operates the valve *W*, through the lever *J*, connecting bar *M*, and crank-arm *N*, in the usual well-known way. I have shown the disconnecting mechanism as applied to a certain kind of valve. It is not limited to such valve, but may be used in connection with any other valve. The raising of the connecting-rod, when that takes place, may be so adjusted or regulated by the tension of the chain *T* through the arm *g* as to check or stop the engine, par-

tially or entirely, by the chain moving the valve partially or entirely over the ports.

Having thus fully described my invention, what I claim therein as new, and desire to secure by Letters Patent, is—

1. Resting and supporting the wheel, pulley, or its equivalent, upon the belt that drives the governor, so that if said belt should part, break, or slip off from its pulleys the dropping of said wheel and its connected arm will disengage the valve-rod from the governor, and thus avoid any injury incident to such casualty, substantially as herein described.

2. In combination with the arm *g* and the connecting rod *M*, the chain *T* for moving the valve and closing or partially closing the ports, when said rod *M* is disconnected from the governor, for the purpose of stopping or checking the engine, substantially as described.

J. L. HASTINGS.
